UNITED STATES PATENT OFFICE.

FREDERICK S. STRONG, OF EAST BRIDGEWATER, MASSACHUSETTS, AS
SIGNOR TO THE CARVER COTTON GIN COMPANY, OF SAME PLACE.

LEATHER-SPLITTING MACHINE.

SPECIFICATION forming part of Letters Patent No. 91,641, dated January 8, 1884.

Application filed November 15, 1883. (No model.)

To all whom it may concern:

Be it known that I, FREDERICK S. STRONG, a citizen of the United States, residing at East Bridgewater, in the county of Plymouth and State of Massachusetts, have invented certain new and useful Improvements in Leather-Splitting Machines, of which the following is a specification.

My invention relates to that class of leather-splitting machines in which two feed-rolls are used in connection with a fixed knife. Heretofore these machines have been made usually with the upper roller adjustable by cams, which revolve upon non-adjustable axes, and with the lower roll adjustable by screws at each end, and made movable by separate levers. In my device the upper roll is controlled by cams upon a shaft which is adjustable, while the lower roll is adjustable at each end by connected levers, so arranged that a single movement of the foot will depress the lower roll, but not disturb the adjusting device, so that when the foot is removed from the lever the lower roll will return to its position accurately adjusted at each end. I attain these objects by the mechanism illustrated in the accompanying drawings, in which—

Figure 1 is a view, partly in elevation and partly in vertical section. Fig. 2 is a cross vertical section taken through the center. Fig. 3 is a plan. Fig. 4 is an enlarged cross-section taken on line $y-y$ of Fig. 3, showing the arrangement of the housings.

A, Figs. 1 and 2, represents the base and stand of the machine.

B C represent the frame of the machine. D D', Figs. 1 and 2, are the feed-rolls, and E the knife. The upper feed-roll, D, is hung in movable boxes, made as shown at C', Figs. 1 and 4. The lower part of this box C' receives the journal D' of the roller P, while the upper part of the box is recessed for the reception of the spring C', Fig. 4. The lower part of this spring C' rests upon a bridge, C', which passes through the recess in the box C', and is supported at its ends on the pieces c c, attached to the frame C, Fig. 4. The upper end of the spring C' rests against the under side of the upper part of the box C', the tend-

ency of the spring C' being to force the box C' upward, and thus to lift the upper roll, D.

At each end of the shaft K a cam like K², Fig. 4, is attached. These cams rest upon the upper parts, C², of the boxes C', and resist the action of the springs C'. By revolving the cam-shaft K by the hand-wheel K' the cams K² may be turned to occupy any desired position, so as to allow the spring C' to force the boxes C' upward, and thus adjust the upper roller, D, to the work to be done. This cam-shaft K is mounted in adjustable boxes, one at each end, like the box H in Fig. 4. Each of these boxes is fitted in a suitable casing, so that it may be adjusted vertically by means of the screw H'. This screw H' is of the class 65 called "differential"—that is, it has a thread, h, of one pitch, which works in the upper part of the fixed casing, and a thread, h', of different pitch and different tend, which works in the box H, so that by turning the screw H' 70 the ends of the cam-shaft K may be accurately adjusted, and thus any difference of wear of the two cams and their adjuncts may be allowed for.

The lower feed-roll, D', is hung in boxes, one 75 of which is shown at L, Figs. 1 and 4. Each of these boxes L has a projection, L', in which a recess is formed for the end of the lever L², Figs. 1 and 4. Each of the levers L² is hung upon a pivot, L³, one of the levers being supported by the projections B', Fig. 1, and the other by the projection B², Fig. 1. The inner ends of these two levers L², Fig. 1, are connected by a link-piece, M, which is united to the vertical rod M' by a pivot, m, this rod 85 M' being connected by the union-nut N² to the rod M². (See Figs. 1 and 2.) The lower end of the rod M² rests in a recess, P², in the end of the foot-lever P, the foot-lever P being pivoted at P', as shown in Fig. 2.

S is a spring, the upper end of which rests upon an adjustable buttress, N, in the frame B, while the lower end acts against the union-nut N², the tendency of the spring being to force the rod M' downward. This action of the rod M' is communicated to the inner ends of the levers L² L³, so as to bring them down, and consequently their outer ends with boxes L L

upward. In other words, the tendency of the spring S is to force the lower roll, D', upward. This upward motion of the roll D' is adjusted at each end by the device which I will now 5 proceed to describe.

R R, Fig. 1, are screw-rods, each provided with a hand-wheel, R', and each working in a screw-socket, R², Fig. 1, affixed to the frame of the machine.

10 R³ are check-nuts, which serve to hold the screw-rods permanently in place. As these screw-rods R R determine accurately the limit of the downward motion of the levers L¹, they consequently limit the upward motion of the outer ends of the levers—that is, they limit and adjust the two ends of the lower roll, D', so that it (the said lower roll, D') may be accurately adjusted in relation to the knife E.

15 L³, Figs. 1 and 4, is a set-screw located in the lower end of the projection L', and serves to take up the lost motion that would otherwise exist between the lever L² and projection L'.

From the above it may be seen that the user 20 of the machine, by simply depressing the foot-lever P, can bring the lower roll, D', down and out of working position without disturbing the adjusting device, so that when the lever P is released the roll D' will return at once to its exactly adjusted position. The 25 sunk-head knife-holding bolt T, Fig. 2, is provided with a fixed collar, t, against which a

spring, T', acts, the lower end of the spring T' resting upon the shoulder T², the action of the spring being upward, so that when the nut T³ is loosened the bolt T is thrown out by the 35 action of the spring, thus saving the user considerable time, which he would otherwise have to use in getting it out.

I claim as my invention—

1. In a leather-splitting machine, the combination of the upper roll, D, the boxes C' C', springs C² C³, cams K² K³, and shaft K, with the adjustable boxes H H and screws H' H', all operating substantially as described, and for the purpose set forth. 40

2. In a leather-splitting machine, the combination of the lower roll, D', boxes L L, having projections L' L', levers L² L³, and adjusting-screws R R, with the link M, rods M' M², spring S, and foot-lever P, all operating together substantially as described, and for the purpose set forth. 50

3. The combination of the sunk-head knife-holding bolt T, having a fixed collar, t, with the spring T', arranged to operate substantially as described, and for the purpose set forth. 55

FREDERICK S. STRONG.
